TAPE EMBOSsing TOOL

James H. Lee, Oakland, Calif., assignor to Dymo Industries, Inc., Emeryville, Calif., a corporation of California

Filed Jan. 6, 1965, Ser. No. 83,298

Term of patent 14 years

(Cl. D64—10)

FIG. 1

FIG. 2

FIG. 3

FIG. 6

FIGURE 1 is a side perspective view of a tape embossing tool showing my new design;

FIGURE 2 is a bottom perspective view thereof;

FIGURE 3 is a perspective view of the side opposite to that of FIGURE 1;

FIGURE 4 is a top plan view;

FIGURE 5 is a bottom plan view; and

FIGURE 6 is a rear elevational view thereof.

I claim:

The ornamental design for a tape embossing tool, as shown.
